APPARATUS FOR PACKAGING TOW

Walter H. Davis, Jr., Decatur, Ala., assignor, by mesne assignments, to Monsanto Chemical Company, a corporation of Delaware

Filed Mar. 11, 1960, Ser. No. 14,315

8 Claims. (Cl. 28—21)

This invention relates to apparatus for packaging tow and more particularly to apparatus for uniformly and evenly packaging tow, yarn or other filamentary material into containers for shipment or subsequent processing.

Tow and other continuous filamentary material is often packaged into containers for dyeing, annealing or other liquid treating steps, or for shipment of the material to textile mills and other processors. It is highly desirable in so packing yarn to deposit the yarn within the container in a uniform manner so as to fully utilize the space within the container, while at the same time being sure to avoid tangling of the yarn in order to permit subsequent, smooth and easy withdrawal thereof. Though various devices have been suggested for accomplishing the packaging process they have not been completely satisfactory for a variety of reasons. In most cases the devices suggested have been extremely large, complex and unwieldy. Moreover, the prior art devices have not been sufficiently flexible to permit filling containers of various shapes and sizes.

The present invention provides a device for guiding tow or other filamentary materials into a container in a continuous, automatic and uniform manner. Means are provided to guide tow in a path traversing one axis of the area of the container while displacing this path in a direction normal to that axis in response to the completion of said path. A tubular member which directs the tow into the container is supported at its upper end by a ball and socket joint for movement of the lower end in all directions. The lower end of the tube or member, positioned just above the container, is reciprocated across the container in one direction. At the end of each stroke of the tubular member, the lower end thereof is displaced laterally of its direction of reciprocation. The tow is thus fed into the container in such a manner that it is not tangled, twisted or crossed.

It is an object of this invention to provide novel and improved apparatus for packaging tow, yarn or other filamentary material into a container.

It is a further object of this invention to provide an apparatus for feeding tow into a container wherein means are provided to uniformly deposit the tow throughout the area of the container so as to avoid uneven build-up of tow in any section of the container.

It is a further object of this invention to provide a device for packaging tow into containers which is easily adjustable so as to be suitable for filling containers of a wide variety of shapes and sizes.

It is a further object of this invention to provide a device for depositing tow within a container in a smooth manner so as to permit subsequent easy withdrawal within tangling of the tow.

It is a further object of this invention to provide a device for guiding tow into a container wherein the guiding means are oscillated in a path transverse to the area of the container, and wherein means are provided for displacing said oscillating means in a direction normal to said path in response to the completion of each stroke of said guiding means.

Other objects and features of the invention will become apparent as the following detailed description of a preferred embodiment of the invention is read in conjunction with the appended drawings, in which:

FIGURE 1 is a side view of one embodiment of the

2

invention shown partially in section and illustrating a tow container being filled; and

FIGURE 2 is a plan view of the embodiment of the invention illustrated in FIGURE 1 shown partially broken away for purposes of illustration.

Referring now to the drawings, reference numeral 10 indicates a tubular conduit or tow guide having a bottom telescoping portion 12. The conduit 10 is integral with and depends from a hollow universal ball joint 14 which is supported for pivotable movement within a frame 16 of the apparatus. The passage of the hollow universal joint leads to the passage of the conduit 10.

Above the universal joint there are two feed rollers 18 and 20 which are driven in the direction shown by the arrows by a motor and gear reduction drive box 22. A tow 24 is fed from a source (not shown) between the rollers 18 and 20 and thence through the universal joint 14 and the tubular conduit or guide 10. Attached to the bottom of the telescoping portion 12 there are provided a set of advancing rollers 26, only one being visible in the drawings. These advancing rollers are mounted within a roller bracket 28 and are driven by a second motor and gear reduction drive box 30. Reference numeral 32 denotes a lead wire which connects the motor to a power supply (not shown), while reference numeral 34 indicates an output shaft extending from the motor and gear reduction drive box 30 which turns a gear 36 mounted on the shaft of the advancing roller 26.

Rigidly attached to the bottom of the telescoping portion 12 is a shaft 38 having a ball 39 on the end thereof. The ball 39 is positioned within a socket 40 to provide a universal joint. Reference numeral 42 denotes a shaft or linkage extending from the socket 40 to a carriage 44 mounted on a double threaded shaft 46 of a well-known type.

Reference numeral 48 indicates a motor and gear reduction drive box which drives the shaft 46 through a gear box 49 containing beveled gears 50 and 51. Reference numerals 52 and 54 indicate stops which may be positioned at any points along the shaft 46. The carriage 44 and the double threaded shaft 46 comprise a conventional reciprocal screw and nut mechanism, wherein a pawl (not shown) of a well-known type is provided within the carriage for engaging the threads of the shaft 46 for movement in one direction along the rotating shaft until one of the stops 52 or 54 is contacted, whereupon the pawl is shifted to the reverse threads on the shaft 46 so as to reverse the direction of travel of the carriage. In this manner, the reciprocal motion of the carriage 44 along the shaft 46 is achieved.

Mounted on the carriage 44 is a contact switch 46 having depressable pins 57 and 58. The operation of this switch will be more fully explained in connection with the operation of the apparatus, the purpose of the switch being to cause a reversal of direction of the carriage 44.

Reference numerals 59 and 60 indicate bushings which support the shaft 46 by means of brackets 47 and which are adapted for axial movement along two parallel double-threaded shafts 62 and 64. Reference numerals 66 and 68 indicate the bearings within which the shafts 62 and 64 are rotatably mounted. Reference numerals 70 and 72 denote stops which may be fixed at any point along the shafts 62 and 64. Here too, the carriages 58 and 60 are provided with pawls (not shown) of a well-known type to permit reversal of travel along the shafts 62 and 64 when the carriages 59 and 60 strike the stops 70 and 72.

Reference numeral 74 indicates a motor and gear reduction drive box which is coupled to a gear box 75 containing beveled gears 76 and 77. The beveled gear 77

is mounted on a shaft 82 which carries worm gear drives 78 and 80. The worm gear 78 drives a gear 84 (FIGURE 1) which is mounted on the shaft 64 to accomplish rotation of this shaft. Rotation of the shaft 62 is similarly achieved, though no gear equivalent to gear 84 has been illustrated in the views shown. Reference numeral 86 denotes a bracket support which mounts the shaft 82 and worm gears 78 and 80 on the frame of the machine.

Reference numeral 88 indicates the container positioned below the tubular conduit or guide 10 and its telescoping portion 12 for receiving the tow 24. The container 88 is positioned on a scale 89 of a well-known type (shown diagrammatically in FIGURE 1) having a switch 90 (FIGURE 2) which opens when a predetermined weight of tow is fed into the container. The scale is adjustable so that the switch 90 may be opened at any desired tow weight. This scale is a conventional type.

A start-stop switch is illustrated at the lower left hand corner of FIGURE 2, and is shown connecting with the motor and gear reduction drive boxes 48, 30, 22, and through a time delay mechanism 92 of a well-known type with the motor and gear reduction drive box 74.

In the operation of the embodiment illustrated, the tow 24 is continuously advanced by the feed rollers 18 and 20 through the conduit or guide 10 downward by the advancing rollers 26 into the container 88. As shown, the conduit 10 is supported by the universal ball joint 14 for universal pivotal movement. The bottom of the telescopic portion 12 is carried on the carriage 44 for movement along the double threaded shaft 46. With all motors except the motor and gear reduction box 74 operating, the shaft 46 will be rotated to move the carriage 44 the predetermined distance between the stops 52 and 54. When the carriage reaches one of the stops 52 or 54, the contact switch 56 is actuated to operate the time relay 92 to start the motor and gear reduction drive box 74. Rotation of the shaft 62 and the shaft 64 is then carried out for a predetermined time, for example one second, whereupon the shaft 46 is moved to the left along the shafts 62 and 64 while still rotating. The carriage 44, having reversed its direction of travel upon hitting the stop 54, next completes its stroke by hitting the stop 52 whereupon the contact switch 56 again actuates the time delay mechanism 92 to move the carriages 58 and 60 along the shafts 62 and 64 for another predetermined period.

In short, upon the completion of each stroke of the carriage 44 along the shaft 46, the shaft 46 is carried by the carriages 58 and 60 to the left. Thus, the tow which is continually issuing from the open end of the telescoping section 12 is deposited in substantially parallel rows along the entire width of the container area. When the carriages 58 and 60 reach the stops 70 and 72 which have been positioned at the desired point in relation to the area of the container, these carriages reverse their direction of travel and move toward the right upon the completion of each stroke of the carriage 44 along the shaft 46.

As is apparent from the drawing and particularly from FIGURE 2, the stops 52 and 54 may be positioned in relation to the stops 70 and 72 so as to deposit the tow along any desired area within the container 88. Thus, the disclosed embodiment can be adjusted to fill containers of various sizes.

It is seen that the tow guiding means in the embodiment illustrated reciprocates rapidly along the shaft 46 across the area of the container in one direction while this shaft is moved more slowly in a path normal to the reciprocating path by virtue of the worm gear drives 78 and 80.

Obviously many modifications and variations of the present invention are possible in the light of the above teachings. It is, therefore, to be understood that within the scope of the appended claims, the invention may be practiced otherwise than as specifically described.

What is claimed is:

1. An apparatus for packaging tow into a container, comprising a support carrying a universal joint disposed generally axially above said container, a tubular conduit depending from said joint for pivotal movement thereabout, means to continuously pass tow through said conduit, means connected to the conduit for continuously reciprocating said conduit in a path transverse to said container, and means responsive to a stroke of said conduit to displace said conduit in a direction normal to said path.
2. The apparatus of claim 1 wherein said universal joint has a hollow ball the passage of which is connected to the passage of said tubular conduit.
3. The apparatus of claim 1 including means to reverse the direction of displacement.
4. An apparatus for packaging tow into a container, comprising a frame, a tubular guide pivotally mounted at one end thereof above the container, a first double-threaded shaft rotatably mounted on the frame, a first carriage mounted on the first double-threaded shaft, first means on the frame for rotating the first shaft to move the first carriage along said shaft, a second double-threaded shaft mounted on the first carriage normal to the first shaft, a second carriage mounted on the second shaft and connected to said other end of the tubular guide, second means for rotating the second shaft to reciprocate said other end of the guide, and means for actuating said first rotating means in timed relationship with the reciprocations of the guide.
5. An apparatus for packaging tow into a container, comprising a frame, a tubular guide pivotally secured at the upper end thereof to the frame and having the lower end thereof positioned above the container, a first pair of parallel double-threaded shafts mounted on the frame, a pair of first carriages mounted on said first double-threaded shafts, first means for rotating said first shafts to advance the first carriages therealong, a second double-threaded shaft mounted on the first carriages and positioned normal to said first shafts, second means for rotating the second shaft to reciprocate the second carriage along said second shaft, a linkage interconnecting the second carriage to the lower end of the guide so that said lower end of the guide is reciprocated with said second carriage, means on the guide for advancing the tow therethrough, means for actuating the first rotating means for a predetermined time interval in response to each of the strokes of the second carriage, and means for disabling the apparatus when a predetermined amount of tow has been deposited in the container.
6. Apparatus for packaging a tow, comprising a frame, a tubular conduit having on one end thereof a ball, means on the frame engaging the ball to form a ball-joint suspension of the conduit, means connected to the conduit for reciprocating the other end of the conduit in a first direction, and means connected to the conduit for displacing said other end laterally in response to the completion of a stroke of said other end in said first position.
7. An apparatus for packaging a strand, comprising a base, a first threaded shaft rotatably mounted on the base, a carriage mounted on the first shaft for movement therewith as said first shaft is rotated, a second threaded shaft rotatably mounted on the carriage, a second carriage mounted on the second threaded shaft for movement therewith as said second threaded shaft is rotated, an elongated guide connected at one end to the second carriage for directing a strand into a container, said guide having at the other end thereof a ball attached to the base in a ball-joint relationship, means for continuously rotating the second threaded shaft to move the guide in a first direction, and means responsive to the completion of a stroke of travel of said guide in said first direction for rotating the first shaft for a predetermined time interval to move the guide a predetermined distance.
8. Apparatus for packaging a tow, comprising a frame,

a socket on said frame, a ball mounted in the socket and having an aperture therethrough, a conduit attached at one end to the ball and interconnected with said aperture, a pair of parallel shafts rotatably mounted on the frame, said shafts being reversely threaded, a pair of carriages mounted on the shafts in such a manner that rotation of said shafts moves the carriage, a third shaft rotatably mounted on the carriage, said third shaft being reversely threaded, a third carriage mounted on the third shaft and connected to the other end of the conduit, means for rotating the third shaft continuously to reciprocate said other end of said conduit in a first direction, means connected to said pair of shafts for driving said shafts for a predetermined time interval, and means responsive to

5 completion of a stroke of said conduit for actuating the driving means.
